UNITED STATES PATENT OFFICE

143,565

DESIGN FOR A DECK OF PLAYING CARDS OR THE LIKE

Adolph F. von Soden, Los Angeles, Calif.

Application April 24, 1945, Serial No. 119,177

Term of patent 7 years

(Cl. D34—13)

To all whom it may concern:

Be it known that I, Adolph F. von Soden, citizen of a country not known, residing at Los Angeles, in the county of Los Angeles, State of California, have invented a new, original, and ornamental Design for a Deck of Playing Cards or the like, of which the following is specification, reference being had to the accompanying drawings forming a part thereof.

This is a continuation-in-part of application Ser. No. D-111,248 filed October 1, 1943.

Figs. 1, 2 and 3 are face views of certain cards of the deck of playing cards, showing my new design.

Fig. 4 shows the back face of the cards.

The cards from each suit numbered from 3 to 10 are conventional as to suit indicia, being otherwise like the cards numbered 2 in Figs. 2 and 3.

I claim:

The ornamental design for a deck of playing cards or the like, as shown and described.

ADOLPH F. VON SODEN.
